Primary Examiner—A. Hugo Word*Assistant Examiner*—Doris Clark*Attorney, Agent, or Firm*—Stanley Price, Jr.**[57]****CLAIM**

The ornamental design for a spacer joint for use in a block wall, as shown and described.

DESCRIPTION

FIG. 1 is a perspective view of a spacer joint for use in a block wall showing my new design;

FIG. 2 is a front elevational view thereof;

FIG. 3 is a fragmentary side elevational view thereof;

FIG. 4 is a fragmentary top plan view thereof;

FIG. 5 is a perspective view of a second embodiment of a spacer joint for use in a block wall showing my new design;

FIG. 6 is a front elevational view thereof;

FIG. 7 is a fragmentary side elevational view thereof; and,

FIG. 8 is a fragmentary top plan view thereof.
